UNITED STATES PATENT OFFICE.

WILLIAM S. AUCHINCLOSS, OF WILMINGTON, DELAWARE.

IMPROVEMENT IN RAILWAY-CAR AXLE-BOXES.

Specification forming part of Letters Patent No. 121,572, dated December 5, 1871.

To all whom it may concern:

Be it known that I, WILLIAM S. AUCHINCLOSS, of Wilmington, in the county of New Castle and State of Delaware, have invented a new and useful Improvement in Axle-Boxes for Railroad Cars; and I do hereby declare the following to be a full, clear, and exact description thereof, which will enable others skilled in the art to make and use the same, reference being had to the accompanying drawing forming part of this specification, in which drawing—

Figure 1 represents a front view of this invention. Fig. 2 is a sectional side view of the same.

Similar letters indicate corresponding parts.

This invention consists in the arrangement of a strap of wrought-iron, steel, or malleable iron extending round an axle-box and round the lug or ear projecting from said box, and forming the bearing for the pin that connects the equalizing-beam with the axle-box in such a manner that the equalizing-beam will be securely supported beneath the axles of the car, and consequently the height of the center of gravity above the rail is materially reduced.

In the drawing, A A' designate the two axle-boxes, which are connected to one and the same equalizing-beam B. This equalizing-beam is situated beneath the axles of the car or truck, and it is connected to the axle-boxes A A' by means of pins a a' passing through lugs b b', which are cast solid with the boxes. The strain produced by the equalizing-beam on the lugs b b' is downward, and in order to strengthen these lugs, and to enable them to support the equalizing-beam without danger of breaking or splitting, I have applied to my box a strap, C, made of wrought-

iron, steel, or malleable iron, and passing round the body of the box and round the lug or ear b or b', as shown in the drawing. This strap may be cast in or on, or shrunk on or attached in any other desirable manner, and it must be made sufficiently strong to preclude all danger of breakage. On some of the boxes I have two lugs, as shown in Fig. 2, both being strengthened by straps; and in this case the end of the equalizing-beam passes in between the two lugs. When the box is provided with one lug the end of the equalizing-beam is made bifurcated, so that it will straddle the lug, as shown on the box A', Fig. 1.

By this construction of the boxes I am enabled to place the equalizing-beam beneath the axles, and by thus reducing the height of the center of gravity from the rails the steadiness of a car in motion is materially increased, an advantage which is of particular value for narrow-gauge roads.

I do not confine myself to the use of the lug or lugs, but can, when it seems desirable, increase the depth of the strap, and thus form a bearing or body for the pivot.

What I claim as new, and desire to secure by Letters Patent, is—

The arrangement on an axle-box of a strap or straps, C, embracing the body of the box and the lug which forms the bearing for the pivot of the equalizing-beam, substantially as set forth.

WM. S. AUCHINCLOSS.
